ENSIGN-BICKFORD COMPANY, OF SIMSBURY, CONNECTICUT, A CORPORATION OF
CONNECTICUT.

MACHINE FOR MAKING FUSES.

1,079,367.

Specification of Letters Patent. Patented Nov. 25, 1913.

Application filed October 12, 1906. Serial No. 338,552.

To all whom it may concern:

Be it known that we, LOUIS SCHULMAN and JOSEPH SCHULMAN, citizens of the United States, residing, respectively, in the borough of Manhattan, city, county, and State of New York, and the borough of Brooklyn, city of New York, county of Kings, and State of New York, have invented certain new and useful Improvements in Machines 10 for Making Fuses, of which the following is a specification.

This invention relates to machines for making fuses or combustible stems of the character employed in connection with fire 15 crackers, fire works, blasting cartridges and other explosive and combustible devices, and the main objects of our invention are, first, to produce a fuse of high efficiency the envelop of which is of paper; second, to 20 produce such a fuse continuously in considerable lengths at a high rate of speed; third, to so construct the machine that the various parts thereof shall be readily accessible for repair and control; fourth, to 25 provide for the ready variation in diameter of the fuse within wide limits, and lastly, generally, to improve the character of the product, and to reduce the expense of producing the same.

To these ends, we have provided a machine for twisting one or more strips of paper into rope-like form around a combustible element which is continuously fed to the strip during the forming operation 35 thereupon. In order to attain the required speed of operation and to obviate fractures, we have so constructed and arranged the parts as to oppose the least resistance to the formation and travel of the fuse elements 40 and furthermore, we have rendered the strip pliable by thoroughly moistening the same before it is acted upon in a forming operation.

Our invention also consists in many novel 45 details of construction and combinations of parts such as will be more readily understood by a detail description of a machine in which our invention is embodied, and to this end, we will now proceed to describe 50 such a machine with reference to the accompanying drawings illustrating the same, and will then point out the novel features in claims.

In the drawings: Figure 1 is a view

partly in front elevation, and partly in section of a machine constructed in accordance with the present invention. Fig. 2 is a view in horizontal transverse section of the same upon the plane of the line 2—2 of Fig. 1, and looking in the direction of the arrow. 60 Fig. 3 is a similar sectional view looking in opposite direction. Fig. 4 is a detail vertical sectional view upon an enlarged scale through the forming members and feed reservoir of the machine. Fig. 5 is an enlarged 65 detail view in side elevation of the forming nozzle showing a portion of the strip as being formed around the same together with a sectional view of a portion of the die employed in conjunction with the forming 70 nozzle. Fig. 6 is a detail sectional view upon an enlarged scale through one of the drawing bobbins employed, together with certain correlated parts. Fig. 7 is a detail view in vertical section through certain 75 parts of the main driving means of the machine.

The fuse to be constructed comprises an envelop or wrapping member, and a combustible element wrapped by and contained 80 within the envelop member. The envelop member conveniently comprises a narrow strip of ribbon of paper 10 which is fed from a roll 11 suitably supported in the machine. The combustible element is preferably in the form of a granular material 12 which is contained within a removably mounted reservoir 13. A core element for assisting in the feeding of the combustible material may also be employed, such element 90 conveniently comprising one or more textile threads 14 which are fed from suitable spools 15 through the reservoir as will be presently explained. The paper ribbon 10 is fed angularly toward a hollow tapering 95 forming nozzle 16 located immediately beneath and in line with the reservoir 13, the said reservoir being conveniently provided with a throat piece 17 received within a recessed portion 18 at the upper end of 100 the said nozzle. The nozzle is removably supported in the machine by being mounted in a hub 19 secured to or formed as a part of the frame 20, a set screw 21 being employed for holding the nozzle securely in place. 105 The lower end of the nozzle is received within a counter-sunk portion 22 of a die 23 conveniently mounted in the frame of the ma-

chine, the said die being provided with an opening therethrough longitudinally in line with the opening through the nozzle as will be well understood by reference to Fig. 4 5 of the drawings. The strip 10 is guided over the bracket 19 and passes thence in a helical coil around the nozzle 16 through the die 23, being drawn through the die and twisted as it is being so drawn therethrough 10 by a means located beneath the die, and which will presently be explained. The combustible element 12 is fed continuously through the nozzle from the reservoir and is received within the coiled strip as it leaves 15 the point of the nozzle and enters the die. At this point the strip is in the form of a helical coil and hence is in proper condition to receive the granular material and the feed of the granular material is made more positive 20 where the textile threads 14 are employed as will be well understood, the textile threads acting to draw the granular material down from the reservoir into the coiled strip, and as the strip passes through the die, 25 it is twisted into rope-like form so that all the component parts of the fuse become intimately associated.

Rotatively mounted beneath the forming element of the machine is a frame 24, the 30 axis whereof is longitudinally in line with the axis of the said forming element. The frame is provided, at its upper end, with a hub 25 which is journaled in a bearing 26 secured to or formed as a part of the frame 35 20 of the machine, and at its lower end the said frame is provided with a sleeve 27 (see Fig. 7) which is disposed upon a central stud 28 secured fast to a hub 29 secured to or formed as a part of the said frame 20. 40 The frame is arranged to be driven by a drive shaft 30 through the medium of a pair of bevel gears 31 and 32, the former of which is secured upon the drive shaft, and the latter disposed loosely upon the sleeve 45 27. A clutch member 33 is splined upon the sleeve 27 and is provided with an operating handle 34 by which it may be moved longitudinally upon the said sleeve; the face of the said clutch member is provided with 50 teeth for co-engagement with complementary teeth disposed upon the hub of the bevel gear 32. Near its upper end the frame is provided with a disposing member comprising two spools or bobbins 35, the said 55 spools or bobbins being rotatively mounted upon studs 56 secured fast to the said frame. Each of the said bobbins has secured fast to it a spur gear 36, the said spur gears being each arranged in mesh with a central 60 pinion 37 disposed fast upon the lower end of a stationary hollow guide tube 38. This gear connection will result in movements of rotation being imparted to the spools or bobbins about their own axes when the 65 frame 24 is rotated, while the said spools or

bobbins will also be given a planetary movement around the axis of the frame at the same time. The assembled fuse elements, as they leave the die 23 of the forming element of the machine, pass thence down through 70 the hollow guide tube 38 to a direction roll 39, located near the base thereof; thence they pass around the spools or bobbins 35, preferably several times around the same, and thence over several guide rolls 40, 41, 75 42 to a distributing arm 43 and thence to a take-up drum 44. The distributing arm 43 is given a traversing movement over the drum 44 by means of a cam 45, a follower arm 46 and a link 47 by which the said arm 46 is connected to the distributing arm 43, the said cam 45 being mounted upon a shaft 48 suitably journaled in the frame 24. The said shaft has a worm wheel 49 mounted thereon, the teeth of which are in mesh with a worm 50, disposed upon a shaft 51, and the upper end of the said shaft 51 is provided with a gear 52, the teeth of which are disposed in mesh with the teeth of one of the wheels 36. 80 85

The drum 44 is conveniently mounted loosely in the frame, being provided with a spindle 53, the lower end of which is adapted to be received within the upper end of the sleeve 27 of the frame 24. The frame 90 is conveniently provided with a platform 54 for supporting the lower flange of the drum. The drum is driven by frictional engagement with the frame, the speed of drive being preferably somewhat greater than is necessary when the drum is fully wound whereby the drum may be driven at a sufficient speed to take up the fuse fed thereto by the bobbins 35. Frictional engagement of the drum with the frame will of course 95 permit required lost motion to compensate for this excess drive.

Near the upper end of the machine, we have provided a roller and reservoir 55 as a means by which the paper element may be 100 treated before it is received by the forming element. The reservoir preferably contains a liquid paste for the purpose of giving sufficient adhesive property to the strip to cause it to permanently form itself around the combustible element in the formation of the fuse, the paste or other material having also the effect of increasing the pliability of the strip so as to reduce the danger of fracture while it is passing through the forming element. To further insure the proper and continuous feed of the combustible material, we have provided means for vibrating the reservoir consisting of a bell-crank lever, the upper arm 57 of which is disposed contiguous to the exterior of the reservoir, and the lower arm 58 of which is arranged to be engaged by a knocker 59 carried by the frame 24. In the rotation of the frame, the knocker 59 strikes the arm 58 of the bell- 110 115 120 125 130

crank lever and causes the arm 57 to strike the reservoir thereby vibrating the same with the result that the granular material is constantly shaken down to the bottom of the reservoir and is prevented from unduly hanging against the sides thereof.

The operation of the machine will be readily understood from the foregoing description taken in connection with the accompanying drawings, but the following is a brief summary thereof.

Considering the machine as in continuous operation, the rotation of the frame 24 in imparting planetary movements to the 15 spools or bobbins 35, and in addition rotational movements about their own axes, will draw the combined fuse elements through the guide tube 38 and the die 23 of the forming member, while at the same time twisting 20 the same into rope-like form. This drawing of the elements will cause the strip 10 to be unwound from the roller 11 to pass over the paste or moistening roll of the reservoir 55, and around the nozzle 16, while at the same 25 time, it will draw the textile threads 14 from their spools 15 and the granular combustible material 12 in a continuous stream from the reservoir 13. The finished fuse will be taken up upon the drum 44 as fast as 30 it is fed thereto being evenly disposed upon the drum by the distributing arm 43. As has been above stated the twisting operation upon the fuse elements results in first forming the strip into a helical coil around the 35 nozzle 16 of the forming element, and then twisting it into rope-like form at a point below the said nozzle after it has received the granular material 12. The paste presented thereto from the reservoir 55 causes 40 the fuse elements to adhere together and to become set in the form to which they are reduced.

It will, of course, be understood that in first threading up the machine it will be 45 necessary to pass the textile threads down through the reservoir, the forming member, and the die tube, and then to unwind a portion of the strip 10 from the roll 11 to pass the same angularly around the nozzle 16 to 50 form a helical coil, and then to pass the end thereof around the threads and to draw the threads and twisted strip around the direction pulley 39, thence around the spools 35 and thence around the direction rollers 55 through the distributing arm to the take-up roll. Thereafter the action of the machine is continuous until the drum has become filled, and thereafter it is only necessary to 60 cut the fuse near the drum and to remove the drum, and immediately place another one in position and connect the cut end to the drum. The starting and stopping of the machine is, of course, controlled by the lever 34.

Having thus described our invention, we

claim and desire to secure by Letters Patent:

1. In a machine for making fuse, the combination of a fixed hollow nozzle, a fixed die below the nozzle, means for feeding paper in strip form about the exterior of the nozzle to form a tube, means for supplying a combustible to the interior of the nozzle whereby said combustible will be delivered to the interior of the tube as it is being formed, and means below the nozzle for bodily twisting that portion of the fuse element comprising said tube and the combustible therein, which is between the nozzle and twisting means; the die being arranged so as to receive the tube after being formed about the nozzle and for causing a contraction of the tube while being drawn through the die.

2. A machine for making fuse comprising in combination a hollow nozzle, means for feeding a strip about the nozzle for the purpose of forming a tube from said strip, means for feeding a combustible material to the interior of the nozzle whereby the combustible will be fed to the interior of the tube as it is being formed, a fixed die through which the tube is drawn during its formation after it has left the nozzle and means for drawing through said die the fuse element which comprises said tube and the combustible material therein, said means also serving to bodily twist said fuse element during its transit from the nozzle to the die.

3. In a machine for making fuses, the combination with a hollow tapering forming nozzle and means for feeding a combustible element therethrough, of means for guiding a strip of paper angularly around the nozzle, a take-up means, a bobbin arranged to receive the product from the nozzle, and means for rotating the bobbin upon its axis, and also with respect to the axis of the bobbin for the purpose of simultaneously twisting the paper below the nozzle and drawing it past the nozzle while the combustible element is being fed to the portion being twisted.

4. In a machine of the character described, the combination with a removably mounted reservoir having a throat piece, a removable tapering forming nozzle arranged in line therewith and recessed to receive the throat piece, and a die arranged in line with the nozzle, of means for feeding a granular material from the reservoir through the nozzle and die, means for guiding a strip of paper angularly around the nozzle and through the die, and means for twisting the paper below the nozzle, and for drawing the same through the die.

5. In a machine of the character described, the combination with a forming member and means for feeding a strip thereto, of a frame arranged to rotate about an axis longitudi-

- nally in line with the said forming member, a bobbin carried by the said frame with its axis eccentric to the axis of the frame but parallel thereto, means for rotating the bobbin about its axis to draw the strip from the forming member, and means for simultaneously rotating the frame to simultaneously twist the strip below the forming member.
6. In a machine of the character described, 10 the combination with a forming member and means for feeding a strip thereto, of a frame arranged to rotate about an axis longitudinally in line with the said forming member, a plurality of bobbins carried by the 15 said frame, with their axes eccentric to the axis of the frame but parallel thereto, means for rotating the bobbins about their axes to draw the strip from the forming member, and means for simultaneously twisting the 20 strip below the forming member.
7. In improvements of the character described, the combination with a forming member, of means for drawing and twisting the fuse elements through the forming member, said means including a plurality of bobbins, and means for rotating the bobbins around the forming member, and means for feeding granular material to the fuse 25 elements.
- 30 8. In improvements of the character described, the combination, with a fuse forming member, of an actuating member comprising a rotating frame, a reservoir feed member, and a vibration member comprising a cranked lever provided with a head arranged to play upon said feed reservoir and with a head arranged to be engaged in the rotation of said frame.
9. In improvements of the character described, 40 an actuating member comprising a rotating frame, and a disposing member carried by said rotating frame and comprising means operated in the rotation of said frame for advancing the completed product in a to and fro course, a drum for receiving the completed product, and means for distributing the completed product upon the drum consisting of an oscillating arm operated in the 45 rotation of said frame.
- 50 10. In improvements of the character described, the combination with a forming member, of means for drawing and twisting the fuse elements through the forming member, said means including a device whereby 55 the fuse is advanced in a to and fro course and a drum upon which the completed fuse is wound, and means for distributing the fuse upon the drum.
11. In improvements of the character described, the combination, with a combustible element feed member comprising a reservoir provided with an open end; of a forming member comprising a die and a nozzle located between said die and said open end of said reservoir, said die being provided with a countersunk portion adjacent to said nozzle, and the end portion of said nozzle adjacent to said countersunk portion of said die being tapered.
12. In improvements of the character described, 70 the combination, with a fuse forming member, of an actuating member comprising a rotating frame, and a disposing member carried by said rotating frame and comprising means operated in the rotation 75 of the said frame for advancing the completed fuse in a to and fro course, a drum for receiving the completed fuse, and means for distributing the completed fuse upon the drum consisting of an oscillating arm 80 operated in the rotation of said frame.
13. In a machine for making fuses, the combination with a forming member comprising a hollow tapering nozzle and a die arranged coincident with the said nozzle, 85 and provided with a counter-sunk portion for receiving the tapered end of the nozzle, of means for feeding a combustible element through the nozzle and die, means for guiding a strip of paper angularly around the 90 nozzle, and means for twisting the paper below the nozzle and for drawing the same through the die.
14. In a machine of the character described, 95 the combination with a forming nozzle, of means for guiding a strip of paper angularly around the nozzle, a bobbin arranged to receive the paper from the nozzle, means for rotating the bobbin about its axis and also with respect to the axis of the 100 bobbin for the purpose of simultaneously twisting the paper below the nozzle and drawing it past the nozzle, the twisting of the paper starting to take place adjacent to the point of delivery from the nozzle, and 105 means for supplying a burning medium to the strip after it has started to be affected by the twisting means.
- In testimony whereof, we have signed our names to this specification in the presence of 110 two subscribing witnesses.
